UNITED STATES PATENT OFFICE.

JOHN HARRIS, OF BRANTFORD, ONTARIO, CANADA, ASSIGNOR TO A. HARRIS, SON & CO., (LIMITED,) OF SAME PLACE.

REAPING-MACHINE.

SPECIFICATION forming part of Letters Patent No. 252,764, dated January 24, 1882.

Application filed September 9, 1881. (No model.)

To all whom it may concern:

Be it known that I, JOHN HARRIS, of the city of Brantford, in the county of Brant, in the Province of Ontario, Canada, manufacturer, have invented certain new and useful Improvements in Reaping-Machines, of which the following is a specification.

The principal object of the invention is to construct and arrange the rake-arms of a reaper in such a manner that they will operate independently of each other with the least possible friction upon their wearing parts; and it consists essentially in making the spindle upon which the rake-holder is hinged so that its longitudinal axis will intersect the axis of the joint by which the arm is hinged to the crown-wheel; also, in similarly arranging the spindle upon which the friction-roller attached to the rake-holder is supported, so that the said friction-roller will at all points revolve freely while traversing the guiding-tracks on the rake-jack.

Figure 1 is a perspective view of my rake-jack. Fig. 2 is a detail showing the relative position of the rake-spindle and friction-roller. Fig. 3 is an enlarged detail of the rake-arm and rake-holder. Fig. 4 is a cross-section through *xy*, showing notch in the arm for preventing the rake-holder revolving, while permitting it to roll up sufficiently to clear the rake of the grain. Figs. 5 and 6 are details of the friction-roller. Fig. 7 is a detail of my improved automatic tripping device.

In the drawings, A is a rake-arm, hinged to the crown-wheel B upon the joint-bolt C. A center line passing through the extension of the arm A, forming the spindle to support the rake-holder D, would intersect the center of the joint-bolt C. The rake-holder D is provided 40 with a projecting arm, D', formed substantially as shown; and having a hub bored out to receive and support the friction-roller, as hereinafter explained.

E is a friction-roller, bored out to fit over the sleeve F. This sleeve is provided with an eccentric hub, which fits into the recess in the hub on the projecting arm D'. The bolt G passes through the center of the sleeve F and secures the friction-roller E in position, as represented. A center line drawn through the

bolt G, if extended, will pass through the center of the joint-bolt C, and also through the center of the main king-bolt, passing through the rake-jack. The center line of the rake-arm also, if extended, will pass through the king-bolt 55 referred to. By thus centering the rake-arm and friction-roller upon the joint-bolt and king-bolt as explained the wear on the friction-roller will always be even.

It will be noticed that I use no spring in 60 connecting the rake-holder to the rake-arm, as it is not intended that the rake-holder should roll around the arm except sufficiently to clear itself from the grain at the point where it is withdrawn therefrom by the cam-track. A 65 notch, a, is made in the arm A to receive a projection, b, formed on the rake-holder D. This projection will prevent the arm rolling on the rake-holder D, but at the same time the notch is sufficiently wide to permit the rake-holder to tilt up in order that the teeth may be clear of the grain when the rake is being raised up either on the grain side or grain-delivery side of the reaper-table.

With the view of explaining the advantage 75 of my invention, I shall proceed to explain its operation in connection with the guiding-track.

As shown in Fig. 1, the rake-holder (marked D²) is being admitted through the gate as it 80 passes from below the guiding-track H to the upper side of the track H', which latter carries it over the table when the rake is to be used only for reeling. While passing from below the track H to the upper side of the track 85 H' the rake-holder is slightly canted by the grain, the notch a being, as I before said, sufficiently wide to permit of this motion, which allows the rakes to clear themselves of the grain as they reel it over the cutters. Owing 90 to the fact that the axis of the friction-roller E is on a center line with the center of the joint-bolt C, and that the center line of the rake-holder is directed to the same point, the friction-roller E will revolve quite as freely below the track H as it will when above the track H², notwithstanding the difference of the angle to the center of the rake-jack. This fact insures a free movement of the friction-roller and prevents the sliding movement which 100

would otherwise be caused when the angle of the rake-arm was altered. The rake-holder D³ is shown as it passes through the gate on the delivery side of the table after having passed over the table. At this point it ascends the driving-track, (not shown in the drawings,) gradually assuming the vertical position that the other arms are shown in. Owing to the centering of the friction-roller and rake-holder, as described, the friction-roller will continue to revolve freely during its passage over this track.

In order that the friction-roller may readily be adjusted to bear properly on the bottom of the guiding-tracks H, the sleeve F, upon which the friction-roller is supported, is provided, as I stated before, with an eccentric hub, which fits into the recess made in the hub of the projecting arm D'. Thus by loosening the bolt G the sleeve may be adjusted around so as to throw the friction-roller nearer to or farther from the track without altering its center line, which at all times will point to the center of the joint-bolt C, as shown in Fig. 3. On reference to Fig. 3 it will be noticed that the rake-holder D has two slots, I, made in it, through which the bolts J, which secure the rakes to the holder, pass. These bolts also pass through washers K through holes eccentrically made in them. The washers are held between the lugs L, cast on the rake-holder D. As the bolts J, which hold the rake to the holder, pass through holes eccentrically placed in the washers K, the said bolts may be adjusted by turning the washers on their center, so that the rake may be raised at both ends simultaneously, or one end alone may be adjusted, as circumstances require.

As the present invention relates to improvements made in rake-gear previously patented by me, it is not necessary to show all the parts or to explain how it operates in connection with the rest of the machine.

In Fig. 7 I show a bell-crank for tripping the gate. This device is designed so that the tripping can either be done automatically by means of pins M, placed in the crown-wheel B, or by means of the foot through a rod connected to the crank N³. This movement is already in public use. It is therefore not necessary to explain its operation; but I may state that as formerly made the crank N was in one solid piece; consequently when the pins M were arranged in the crown-wheel B to trip the rake at certain points the movement is positive and the rake must necessarily be tripped as the pin passes the crank. This was found to be a disadvantage, as it sometimes occurred that it was not advisable to trip the rake at that particular point. In order therefore to have the advantage of an automatic trip, and at the same time be able to control it, I divide the crank N into two parts, N' and N², one of which, N², is rigidly fastened to an arbor fastened to the crank N³, while the other, N', is pivoted to said arbor, the two being pressed apart by the spring

O between them. When the pin M comes in contact with the part or arm N' the crank N³ is caused to revolve, drawing with it the rod which operates the gate. Should the driver find it not advisable to trip the gate at any particular point, he places his foot on the foot-lever which is connected to the arm N². By holding this lever the crank N³ is prevented turning. The pins, when they come in contact with the crank-arm N', turn it on its own axis against the pressure of the spring sufficiently far to enable the pin to pass without affecting the crank-arm N', the spring O being pressed sufficiently to allow the pin to pass without affecting the crank N³. By this arrangement all the advantages of an automatic trip are secured, while at the same time it is kept under the control of the driver.

What I claim as my invention is—

1. In a harvesting-machine having continuously-revolving reeling and raking mechanism, a rake-arm having a spindle upon which the rake-holder rotates, said arm made so that the axis of its spindle, if prolonged, would strike the axis of the joint-bolt connecting it to the crown-wheel, in combination with a friction-roller attached to the rake-holder and working upon a stud, the axis of which, if prolonged, would strike the axis of the joint-bolt and also the axis of the crown-wheel, for the purpose of allowing the friction-rollers to track smoothly on its guide at all points in the revolution of the crown-wheel and in the rotation of the rake upon the spindle of the rake-arm, substantially as described.

2. A rake-arm hinged to the crown-wheel and carrying a rake-holder hinged thereon, the axis of the hinge, if prolonged, intersecting the axis of the joint-bolt connecting the rake-arm to the crown-wheel, and the friction-roller supported on the rake-holder, its axis, if prolonged, also intersecting the pivot of the rake-arm, in combination with a gate hinged to the guiding-track at an opening in said track on the grain side of the machine, for the purpose of raising the rake-arm, rake-holder, and rake, after passing the cutters, to pass over the grain on the platform.

3. In combination with a rake-arm hinged to the crown-wheel, a rake-holder hinged thereon, said rake-holder having a downward and inward inclined projecting arm provided with a friction-roller centered on the axis of the joint-bolt, as described, and a projection adapted to engage with a notch in said arm to permit a slight movement of the rake-holder, so that when the teeth of the rake have passed the cutters and come in contact with the grain the rake-head is thrown into a slanting position, for the purpose of preventing the rakes, when reeling, from disturbing the grain on the platform when the rakes are raised to pass over the platform.

4. A rake-arm hinged to the crown-wheel and carrying a rake-holder hinged thereon, said rake-holder having a downward and inward in-

clined projecting arm provided with a friction-
5 roller centered on the axis of the joint-bolt, as
described, in combination with a projecting
flange secured to or cast upon the guiding-
track at a point just in front of the cutter-bar,
for the purpose of keeping the rakes in a ver-
tical position when reeling the grain to the
cutters.

10. A rake-arm hinged to the crown-wheel
and carrying a rake-holder hinged thereon,
said rake-holder having a downward and in-
ward inclined projecting arm provided with a
friction-roller centered on the axis of the joint-
bolt, as described, in combination with a gate
15 hinged to the guiding-track at an opening on
the grain side of the machine, which, when
closed, causes the rakes to keep a vertical po-
sition and sweep the grain from the platform.

6. A rake-arm hinged to the crown-wheel
20 and carrying a rake-holder hinged thereon, said
rake-holder having a downward and inward in-
clined projecting arm provided with a friction-
roller centered on the axis of the joint-bolt, as
described, in combination with a movable track
25 or throat at the delivery side of the platform,
for the purpose of controlling the delivery of
the sheaf in different conditions of crop.

7. A rake-arm hinged to the crown-wheel
30 and carrying a rake-holder hinged thereon, said
rake-holder having a downward and inward in-
clined projecting arm provided with a friction-
roller centered on the axis of the joint-bolt, as
described, in combination with eccentric wash-
ers and stop in the rake-holder, for the purpose

of adjusting the rakes at either end to the 35
platform.

8. A rake-arm hinged to the crown-wheel
and carrying a rake-holder hinged thereon, hav-
ing a downward and inward inclined project-
ing arm provided with a friction-roller cen- 40
tered on the axis of the joint-bolt, as described,
in combination with the cam-stud on which
said roller revolves, for the purpose of adjust-
ing the roller to the guiding-track.

9. The lever N, consisting of two parts, N' 45
N², and the spring O between said parts, in
combination with a crown-wheel having suit-
able projections for operating said lever and con-
nections, substantially as described, between
the lever and the gate in the guiding-track, as 50
set forth.

10. In a harvesting-machine having continu-
ously-revolving reeling and raking mechanism,
a rake-arm, the axis of its spindle, if prolonged,
intersecting the axis of the joint-bolt connect- 55
ing it to the crown-wheel, and a rake-holder
hinged on said arm, in combination with a fric-
tion-roller attached to the rake-holder and
working upon a stud, the center line of which,
if prolonged, would intersect the axis of the 60
joint-bolt, and also the axis of the crown-wheel,
for the purpose of allowing the friction-roller
to track smoothly on its guide at all points in
the revolution of the crown-wheel.

JOHN HARRIS.
